UNITED STATES PATENT OFFICE.

HENRY D. HURLEY, OF WEEDSPORT, NEW YORK.

EGG-TESTER.

SPECIFICATION forming part of Letters Patent No. 245,172, dated August 2, 1881.

Application filed March 15, 1881. (Model.)

To all whom it may concern:

Be it known that I, HENRY D. HURLEY, of Weedsport, in the county of Cayuga and State of New York, have invented a new and Improved Egg-Tester, of which the following is a full, clear, and exact description.

The object of my invention is a convenient and efficient device by which eggs may be tested by means of a stream of light, the eggs 10 being contained in a dark chamber.

The invention consists of an upright box, supported upon suitable legs, having two chambers, one for the lamp and one for the eggs, the latter being provided with suitable openings, which are partially closed with disks of 15 soft rubber; also, with openings for the light from the lamp and for viewing the eggs.

In the accompanying drawings, Figure 1 is a central vertical longitudinal section of my invention; and Fig. 2 is a horizontal section of the same, taken through the line *xx* of Fig. 1.

Similar letters of reference indicate corresponding parts.

The upright box may be of wood, with a 25 metal roof or cover, or it may be entirely of metal; or, preferably, the lamp-chamber A of the box may be of wood, with the tin or similar sheet-metal portion *b* secured to it in such manner as to form the egg-chamber B and the 30 roof or cover of the chamber A, as shown.

The partition C between the chambers A and B is formed with the opening *c*, which has secured in it the tube *c'*, of felt or other flexible material, and the outside of this chamber is

35 formed with the corresponding opening *E*, through which the eggs are viewed. This opening is provided with the funnel-shaped tube *F*, the outer end of which is curved to fit the face of a person about the eye, so as to shut 40 out all exterior light when the eggs are inspected. The sides of the egg-chamber B are formed with the large openings D D, large enough to admit the hands of the person using the device. These openings are provided with 45 the perforated disks *d d*, of soft rubber or simi-

lar material, which snugly fit over the wrist and shut out the exterior light.

G represents the lamp, which is of any ordinary construction, and of such height as to bring the flame thereof immediately in front of 50 the opening *c*. This lamp is placed in the chamber A through the door H of the wood portion of the box, and it is provided with the necessary supply of air to support combustion through the holes *ii* in the bottom of the chamber, and the products of combustion are permitted to escape through the chimney in opening K in the top or cover, as shown.

In use the eggs are to be passed into the chamber B by the hands, (the rubbers *d d* 60 shutting out all light by closing upon the hands,) and placed against the inner end of the felt tube *c'*. The chamber now being entirely dark, except from the light that comes from the lamp through the opening *c*, the egg can 65 be viewed and inspected and its quality ascertained in front of this stream of light by viewing the same through the opening *E*, the funnel-shaped tube *F* shutting out all exterior light from that direction, as above stated. 70

Having thus described my invention, I claim as new and desire to secure by Letters Patent—

1. The egg-tester herein described, consisting of a box divided into the chambers A and B, the chamber B being provided with the 75 opening *c* and *E* and with the side openings, D D, the side openings being provided with the perforated disks *d d*, as and for the purposes specified.

2. The chamber B, having the side openings, 80 D D, partially closed by the perforated disks *d d*, and having the openings *c* and *E*, in combination with the tube *F* and flexible tube *c'*, and the lamp-chamber A, substantially as and for the purpose described. 85

HENRY D. HURLEY.
